UNITED STATES PATENT OFFICE

2,550,096

PUSHING IMPLEMENT

Edwin J. Strandberg, Deadwood, S. Dak.

Application April 9, 1948, Serial No. 20,149

1 Claim. (Cl. 254—17)

1

This invention relates to a pushing implement primarily intended for use as a floor jack for positioning boards in abutting engagement to form a flooring and to provide means whereby the individual boards can be held effectively while being secured to the subfloor.

More particularly, it is a primary object of the present invention to provide an implement of the aforescribed character which will not mutilate the subfloor and which is capable of applying sufficient pressure for holding a warped floor board properly positioned while it is secured to the subfloor.

A further and important object of the invention is to provide an implement of the aforescribed character of extremely simple construction yet which will advance a flooring board by direct pressure against the outer edge thereof for correctly positioning it against other floor boards previously applied and having means whereby the leverage of the implement will be varied.

Another object of the invention is to provide a tool having a novel means for detachably anchoring it to a subfloor or other surface at a desired location and which will eliminate striking the implement into the subfloor for accomplishing this result and which method does not promote the accurate positioning of the implement.

Still another object of the invention is to provide an instrument additionally adaptable for use in positioning sheathing boards of walls and which may be employed for pushing and holding heavy objects such as barrels.

Various other objects and advantages of the invention will hereinafter become more fully apparent from the following description of the drawing, illustrating a presently preferred embodiment thereof, and wherein:

Figure 1 is a rear elevational view showing the pushing implement in an applied position, and

Figure 2 is a side elevational view, partly in vertical section thereof.

Referring more specifically to the drawing, the pushing implement in its entirety is designated generally 5 and includes an elongated shank portion 6 having a pair of prongs 7 projecting from one end thereof. The prongs 7 may be either formed integral with the shank 6 or suitably secured thereto as by welding and are provided with tapered ends which project from said end of the shank 6 and which are disposed at a slight angle to the longitudinal axis thereof, as best seen in Figure 2. The prongs 7 are ar-

2

ranged on opposite sides of the shank 6 as seen in Figure 1.

An elongated handle 8 is provided with a longitudinally extending bore 9 which opens outwardly of the lower end thereof for slidably receiving the opposite, upper end of the shank 6 and said handle 8 is provided with diametrically opposed longitudinally extending slots 10 which communicate with the bore 9 and which extend from adjacent the open end of the handle 8 to a point substantially intermediate of its ends. A rod 11 extends through the shank 6 adjacent its upper end and has end portions which slidably engage the slots 10 and headed terminals 12 which are disposed externally of the handle 8. The rod 11 is so located with respect to the upper end of the shank 6 that the handle 8 may slide on said shank within the limits afforded by the slots 10 and it will be readily apparent that the rod 11 will prevent disengagement of the handle 8 from the shank 6. The handle 8 is provided with an externally roughened upper end 13 to provide an effective hand hold and is provided with a solid upper end portion 14 for weighting said handle, for a purpose which will hereinafter become apparent.

The implement 5 also includes a bar or rod 15 composed of the portions 16 and 17 which are disposed at an oblique angle to one another. A work engaging head 18 is suitably secured to or formed integral with the outer end of the bar portion 16 and transversely thereof and the remote end of the bar portion 17 is provided with laterally spaced furcations 19 which project therefrom and the free ends of which are adapted to straddle the shank portion 6 adjacent its lower end and above the prongs 7. Said free ends of the furcations 19 are connected to the shank 6 by a rivet or other headed fastening 20 for pivotally mounting the rod or bar 15 relatively to the shank 6 and handle 8. The portion 17 is of approximately the same length as the combined lengths of the portion 16 and head 18. The distance between the terminals of the prongs 7 and the pivot 20 is greater than one-half the length of the portion 17 and less than the full length of said portion 17.

The implement 5 is shown in Figures 1 and 2 being employed as a floor jack and with the pointed lower ends of the prongs 7 embedded in a portion of the surface of a subfloor 21 to which a number of flooring boards 22 have previously been secured. The implement 5 is disposed so that the head 18 is spaced from the outer edge of the board 22 last secured to the subfloor 21 and

3

so that the next floor board to be secured, as indicated at 23, can be interposed between the head 18 and said last floor board 22. The handle 8 is then grasped by the grip portion 13 preferably with the left hand and swung counterclockwise as seen in Figure 2 or toward its dotted line position whereby the bar 15 and head 18 will be displaced from right to left of Figure 2 to cause the head 18 to engage the outer edge of the bore 23 and to displace it from right to left and into engagement with the adjacent bore 22. The carpenter or user may then position his knee over the shank 6 or handle 8 for holding the board 23 in position while it is nailed to the subfloor 21. The bottom edge of the head 18 is disposed below the level of the underside of the bar portion 16 for contact with the subfloor 21 and so that the bar 15 will be disposed out of engagement therewith. Accordingly, since the bar 15 is composed of the angularly arranged portions 16 and 17 the head 18 will move in a horizontal plane while being advanced from its full line to its dotted line position of Figure 2 due to the fact that the thrust will be along the axis of portion 16 and substantially parallel to surface 21, so that it will directly engage the outer edge of the board 23 for exerting a straight thrust thereagainst in the plane of the boards 22 to permit the board 23 to be properly advanced for engaging the groove thereof with the tongue of the adjacent board 22. Accordingly, where the tongues and grooves of the boards have a very tight fit so that engagement cannot readily be accomplished by merely exerting a push on the board 23, the head 18 may be backed away from the board 23 and the implement then actuated to cause the head to impart a blow to the board 23 to engage its groove with the tongue of the adjacent board 22.

It will also be readily apparent that the handle 8 can be extended upwardly with respect to the shank 6, as previously explained, for increasing the leverage afforded by the handle 8 and shank 6.

In order to properly accomplish the aforescribed operation, it is necessary that the head 18 be initially positioned correctly with respect to the boards 22 and 23 and so that the outer face of the head 18 will be disposed parallel to the adjacent edge of the board 23 and at a correct distance therefrom when the shank 6 is in an upright position. This obviously could not be accomplished if it were necessary to project the shank 6 downwardly for embedding the prongs 7 in the subfloor 21. However, it will be readily apparent that the prongs 7 can be rested on the subfloor 21 and with the head 18, properly positioned as previously described. The

4

handle 8 is then elevated with respect to the shank 6 and then projected downwardly with sufficient force so that the impact of the handle 8 on the shank 6 through the rod 11 will drive the prongs 7 sufficiently into anchoring engagement with the subfloor 21. The weighted upper portion 14 of the handle 8 enables this operation to be readily accomplished with only a slight manual effort.

Various modifications and changes are contemplated and may obviously be resorted to, without departing from the spirit or scope of the invention as hereinafter defined by the appended claim.

15 I claim as my invention:

A pushing implement of the character described comprising an elongated shank, piercing prongs depending from the lower end of said shank and adapted to penetrate a sub-floor 20 surface, work engaging means pivotally connected to the shank adjacent its lower end for engaging and pushing an element when the shank is swung on the embedded prongs as a pivot in one direction, said work engaging means including an arm formed of end portions of approximately the same length disposed at an oblique angle to one another, the terminal of 25 one of said end portions being pivotally connected to the shank and extending outwardly and downwardly therefrom, the distance between the pivot and the free ends of the prongs being more than one-half the length of each end portion and less than the full length of each end portion, the 30 other end portion of said arm being normally disposed at substantially a right angle to the axis of the shank, and a work engaging head at the outer end of said last mentioned end portion having a bottom face disposed below the level of 35 the last mentioned end portion for engaging the 40 sub-floor surface.

EDWIN J. STRANDBERG.
